BY *Victor J. Evans*

ATTORNEY

UNITED STATES PATENT OFFICE.

ARTHUR ROBINSON, OF BRUNSWICK, GEORGIA; J. W. BUGGS, TEMPORARY ADMINISTRATOR OF SAID ARTHUR ROBINSON, DECEASED, ASSIGNOR OF ONE-HALF TO RENA FRAZIER, OF BRUNSWICK, GEORGIA.

METALLIC TIE AND FASTENING MEANS THEREFOR.

1,260,814.

Specification of Letters Patent. Patented Mar. 26, 1918.

Application filed March 28, 1917, Serial No. 158,060. Renewed January 17, 1918. Serial No. 212,367.

To all whom it may concern:

Be it known that I, ARTHUR ROBINSON, a citizen of the United States, residing at Brunswick, in the county of Glynn and State of Georgia, have invented new and useful Improvements in Metallic Ties and Fastening Means Therefor, of which the following is a specification.

This invention relates to metallic cross ties and rail fastening means therefor and has for its primary object, the provision of a tie having upstanding pins or spurs adapted to fit into sockets formed in a rail and hold the latter against lateral movement.

Another object of the invention is to provide a very simple and practical steel railway cross tie having fastening means of simple construction to hold a rail against vertical, lateral and longitudinal movement.

The invention also aims to generally improve railway ties and fastening means to render them more practical, reliable and commercially desirable.

With these and other objects in view as will become more apparent as the description proceeds, the invention consists in certain novel features of construction, combination and arrangement of parts as will be hereinafter fully described illustrated and claimed.

In the drawings,

Figure 1 is a perspective view showing my invention as it appears in use.

Fig. 2 is a fragmentary vertical sectional view.

Fig. 3 is a fragmentary vertical sectional view taken on the plane at right angles to the plane of Fig. 2, and

Fig. 4 is a detail view showing a modified form of pin.

Referring in detail to the drawings by numerals, 1 designates as an entirety a metallic tie having a top wall 2 and side walls 3. The top wall has mounted on it near each end a pair of vertical pins 4. The pins are preferably formed integral with the tie and those in each pair are arranged in transverse alignment.

The rail 5 is of the ordinary type having a ball or tread 6, web 7 and base 8. The rail extends transversely across a plurality of ties 1 and is formed with downwardly

opening sockets 9 to receive the pins 4. The sockets are oblong in cross section so as to allow for a slight longitudinal movement of the rail as is caused by expansion and contraction. The sides 10 of the sockets engage tightly against the opposed sides of the pins to hold the rail firmly against lateral movement. The pins may be made any length desired, but are preferably formed about three inches in length so as to extend through the base of the rail into the web portion thereof.

To hold the rail against vertical movement it is preferable to provide clamps 11 which overlap the base of the rail and which are secured to the tie by suitable fasteners 12.

In Fig. 4, I have shown a modified form of pin designated by the numeral 13. This pin is provided with a reduced end portion 14 which extends snugly through an opening in the top of the tie and which is turned over at its terminal to form a riveting head 15. I do not wish to be limited to any particular method of securing the pin to the tie and may use any other means which would suggest itself.

From the foregoing description taken in connection with the accompanying drawings, it will be apparent that I have provided a very simple and practical metallic rail tie and rail fastening means therefor, which will securely hold a rail against lateral and vertical movement. While I have shown and described the preferred embodiment of my invention, it will be clearly understood that I do not wish to be limited to this construction, but may make such changes as will fall within the scope and spirit of the invention as claimed.

What I claim is:—

In combination with a metallic cross tie, a rail extending transversely thereacross, vertical pins formed on the top of said tie adjacent one end thereof, said pins being arranged in the path of the rail, the rail being formed with downwardly opening sockets to accommodate the pins and clamps secured to the tie and engaging the rail to hold the same against vertical movement.

In testimony whereof I affix my signature.

ARTHUR ROBINSON.

Copies of this patent may be obtained for five cents each, by addressing the "Commissioner of Patents, Washington, D. C."
